UNITED STATES PATENT OFFICE.

CHARLES F. HUMPHREYS AND JOHN C. McCARTHY, OF LANCASTER, PENNSYLVANIA,
ASSIGNORS TO ARMSTRONG CORK COMPANY, OF LANCASTER, PENNSYLVANIA, A
CORPORATION OF PENNSYLVANIA.

SURFACE COVERING AND PROCESS OF ORNAMENTING THE SAME.

Application filed January 22, 1927. Serial No. 162,806.

The present invention relates to surface coverings and process of ornamenting the same, especially to ornamentation of printed, flexible, hard-surfaced floor coverings, by 5 depressing certain of the printed colors so as to bring the color pattern into relief.

The invention is shown as embodied in a so-called imitation handcraft tile floor covering of the type disclosed in the Humphreys 10 patents, Reissue No. 16,510, reissued December 28, 1926, and Reissue No. 16,473, reissued November 16, 1926.

As disclosed in the said Humphreys patents, a hard-surfaced floor covering, such as 15 linoleum, has its surface formed with tile-like spaces which differ in color haphazardly so as to simulate the haphazard arrangement of ceramic tiling, forming what is known as a handcraft tile pattern linoleum.

20 The flexible hard-surfaced floor covering, which comprise linoleum and felt base goods, customarily and particularly in the felt base goods and the cheaper grades of linoleum, have a color pattern printed on the surface of 25 the goods. This is done by printing machines in which printing blocks lay on the various colors in oil paints.

In order to bring out this printed color pattern, we depress certain colors and leave 30 certain colors undepressed. In forming a printed floor covering simulating a tile pattern, we print on the covering certain spaces which are colored to imitate tiling, and between these spaces, other elongated colored 35 spaces, to imitate the mortar joints between the tiles. To bring this colored pattern into relief and still further simulate the appearance of tiling, the colored spaces which simulate the mortar joints are depressed below 40 the level of the spaces which simulate the tiles.

While the present invention is illustrated and specifically described as applied to the ornamentation of a flexible hard-surfaced 45 floor covering having a handcraft tile pattern printed thereon, it is to be understood that it may be embodied in flexible hard-surfaced floor coverings having other patterns.

50 The claims in this application are directed to flexible hard-surfaced floor coverings generically, and to a linoleum floor covering specifically. Claims directed to felt base floor coverings specifically are presented

in our copending application Serial No. 55 206,509, filed July 18, 1927, upon such divisible subject matter.

In the drawings:

Figure 1 is a plan view of a piece of handcraft tile pattern floor covering embodying 60 our invention;

Figure 2 is a plan view of a piece of the material before embossing;

Figure 3 is a section along the line III— 65 III of Figure 2;

Figure 4 is a plan view of a small piece of material after embossing; and

Figure 5 is a section along the line V—V 70 of Figure 4.

Referring to the embodiment of the invention illustrated in the drawings, reference numeral 1 indicates a piece of flexible hard-surfaced floor covering, such as linoleum, having a handcraft tile surface ornamentation. As described in said Humphreys Re- 75 issue Patents Nos. 16,510 and 16,473, the surface is formed for a number of tile-like spaces or units, the different colors being haphazardly arranged to simulate hand- 80 craft tiling.

As shown in the drawings, three kinds of color units are employed to imitate the tile. The units 2 are alike in color, as indicated by horizontal lines; the units 3 are alike in 85 color, as indicated by diagonal lines; and the units 4 are alike in color, as indicated by vertical lines. Usually the units 2, 3 and 4 will be of the same general color but of different shades, to simulate the different shades 90 of burnt tiling which, because of the intensity of the heat at which they are burnt, come out of the kiln with different shades of color; although, if desired, tile-like units of different primary colors may be employed, in case a striking decorative effect is desired. 95 In referring to the colors as "varying colors," we mean either different colors or different shades of the same color.

As further described in said Humphreys reissues the varyingly colored tiles are arranged haphazardly over the area along the strip of linoleum between the points A and B in Figure 1. The pattern thus formed is repeated by the printing operation over successive areas along the strip of the floor covering. The repeat is, of course, necessary because of the machine-printing of the floor covering. The area which is shown in Fig- 105

ure 1 as being the width of the strip of floor covering and in length from A to B, which is repeated in making the floor covering, should be of a sufficient size so that the repeat is not readily apparent to the eye. The minimum size of such repeat areas varies with the size, arrangement and varying colors of the tile-like units. In general, the smaller the individual tile-like units, the smaller the areas over which the arrangement is repeated, and the larger the units and the more striking their appearance, the larger the areas necessary in order that the repeat will not be readily apparent to the eye.

15 As shown in Figure 1, and described particularly in the Humphreys Reissue, No. 16,473, there are preferably units of striking decorative appearance, indicated by reference numerals 5, 6, 7, 8, 9, 10, 11 and 12, interspersed in an apparently haphazard manner to still further simulate hand tiling. These interspersed units are usually of some design differing strikingly in color from the plain tile from which the remainder of the pattern is made.

In order to further simulate the appearance of hand-laid tiling and to obtain an improved artistic effect, we separate the tile-like spaces by printed colored spaces or interliners 13 which imitate the mortar joints between the tiles. The color of the spaces 13 should differ from the color of the tile-like spaces 2, 3 and 4, as the color of mortar varies from the color of ceramic tiling. The variation in color may be that of a different primary color, as for example a black mortar with three shades of red tiling, or the mortar may be of a different shade of the same general color as the tiling.

The printed spaces 13 which simulate the mortar joints are sunk or depressed into shallow grooves 14, as shown in Figures 4 and 5, to simulate the depressed mortar joints occurring in ceramic tiling. The depressed grooves or recesses are relatively shallow, being usually about 1/32 to 3/64 of an inch in depth and with a width corresponding to the width of the colored space which is depressed. The groove preferably has a smooth contour, that is to say, a cross section, as shown in Figure 5, does not present sharp angles or corners, in order to prevent the retention of dirt and allow of easy cleaning. The depressed mortar joints bring the tile pattern into relief. They cause a much better simulation of laid ceramic tiling than plane surface tile pattern floor coverings. The depressions make the colored patterns stand out strikingly. They also break up the smooth light-reflecting surface afforded by a smooth printed floor covering surface. In looking across the room toward a window, the colored pattern of a plane surface floor covering

may be lost in the reflected light, whereas, the same pattern, if brought into relief as herein described, is distinctly visible under the same conditions. The number of varying colors printed on the floor coverings is, of course, limited because of the number of printing heads in the floor covering printing machine. However, by employing a limited number of varying colors for the tile and another color or shade for the mortar joints, with the tile arranged with a studied haphazard appearance, the artistic effect of hand-laid tiling may be secured with the limitations of mechanical printing reproduction, and particularly as the depressed mortar joints give the appearance of the texture of hand-laid tiling.

The printed linoleum or similar flexible hard-surfaced floor covering may be used where hand-laid ceramic tiling would be too expensive or impracticable. They are warm and resilient to the foot and can be laid on any kind of floor. Moreover, they bring a floor covering having the surface appearance of the artistic but expensive hand-laid tiling, into the home of moderate income.

The color pattern which is brought into relief by the surface depressions is formed by color printing over the entire surface of the flexible hard-surfaced floor covering. The colors which are printed on the undepressed portions of the floor covering are brought out strikingly by their prominent position, as contrasted with the color or colors which occur in the depressed portions.

In decorating the flexible hard-surfaced floor coverings, as herein described, the colors may be printed on the surface either before or after the depressions are formed therein. It is preferred, however, to print the colors, preferably with a quick drying paint, prior to the formation of the depressions.

In making a printed embossed pattern linoleum, the linoleum can best be embossed in an uncured condition. To cure linoleum, it is passed into "stoves" in which the oxidizing of the linseed oil binder takes place. If the color pattern be printed on an uncured linoleum with a slow drying paint, the linoleum may become partially cured during the drying of the paint, which usually takes place in the heated chambers which are commonly called "stoves" in the linoleum industry. The curing hardens the linoleum, and it therefore cannot be embossed as satisfactorily as in its more plastic uncured condition. It is therefore preferred in forming a printed embossed pattern linoleum to print the color pattern first, with a quick drying nitrocellulose paint or lacquer which can be dried without curing the linoleum.

This preferred process is illustrated in Fig-

ures 2 to 5. The sheet of linoleum 1, which is formed in the usual way with the usual burlap backing 15 and consolidated linoleum mix 16, has applied thereto the coating of paint 17 printed so as to form the imitation tile color pattern shown in Figure 2. The smooth surface material as thus formed is shown in Figures 2 and 3. This printed material is then put beneath an embossing plate or roller which has ribs which indent the printed spaces 13 into grooves 14.

As shown in the drawings, the entire color imitating the mortar joints is preferably bodily depressed, so that the marginal lines of the depressions or grooves substantially coincide with the lines of juncture between the printed spaces. By thus having a certain color or colors bodily depressed, the colors which are printed on the undepressed portions stand out strikingly by contrast. By having the marginal lines of the depressed portions substantially coinciding with the lines of juncture between the colors, the whole color pattern is brought into sharp relief. If desired, however, the linoleum may first have the desired configuration depressed on its surface, and the color patterns may then be printed on the surface, in which case, however, special precautions have to be taken in order to get the color evenly into the depressed portions. In the printing of felt base goods, the goods may be printed either before or after embossing, although it is preferable to print first and emboss afterwards, especially since the felt base goods would permanently remain more plastic than a linoleum. The asphaltum-impregnated felt will yield under the impress of an embossing plate, even after the goods are printed with an oil paint and the paint dried.

It is preferred to print the floor covering and thereafter to do the embossing with a ribbed embossing plate because by suitably varying the feed of the floor covering to the embossing plate, an accurate matching of the embossing ribs with the printed spaces to be depressed can be achieved. Moreover the embossing has some tendency to stretch and distort the goods. The printing first and the embossing thereafter does away with any inaccuracy of matching between the embossing and the printing which might take place if the goods were first subjected to the embossing operation and should become somewhat stretched thereby.

While it is preferred to emboss entire printed color spaces, as for example, to depress the entire color space imitating the mortar joints on a tile pattern floor covering, the embossing might be otherwise done, as for example, a tile pattern floor covering might be made without the simulation of mortar joints, but having the lines of junc-

ture between the tile-like spaces depressed in order to throw the tile-like spaces into sharper contrast and relief. Also, while we have illustrated the invention as embodied in a handcraft tile pattern design, it may be applied to other patterns. For example, instead of having the tiles arranged with haphazardly varying colors, the tiles may all be printed of the same color. Also floral or other colored figured hard-surfaced floor coverings may have their printed color patterns brought into relief by depressing certain colors of the pattern, leaving other colors standing undepressed. The invention is therefore not limited to its illustrated embodiment, but may be otherwise embodied within the scope of the following claims.

We claim:

1. The process of ornamenting the surface of a flexible hard-surfaced floor covering, which comprises printing on its surface a series of tile-like spaces having a limited number of varying colors arranged in a pattern with irregularity of occurrence so as to simulate the haphazard appearance of hand-laid tiling, and printing between such tile-like spaces elongated spaces colored to simulate mortar joints, and depressing said elongated spaces to simulate the depressed mortar joints of hand-laid tiling.

2. The process of ornamenting the surface of a flexible hard-surfaced floor covering, which comprises printing a color pattern on its surface and thereafter bodily indenting certain of the colors of said pattern to bring the pattern into relief.

3. The process of ornamenting the surface of a linoleum floor covering, which comprises printing a color pattern on its surface, embossing the color pattern, and thereafter curing the linoleum.

4. A flexible hard-surfaced floor covering having a color pattern printed on its surface and having the configuration of the pattern embossed so as to bring it into relief.

5. A flexible hard-surfaced floor covering having its surface printed with a series of tile-like colored spaces having a limited number of varying colors arranged in a pattern with irregularity of occurrence so as to simulate the haphazard appearance of hand-laid tiling, and separated by printed elongated spaces colored to simulate mortar joints, and having the elongated spaces depressed to simulate the depressed mortar joints of hand-laid tiling.

6. A flexible hard-surfaced floor covering having its surface printed with a series of tile-like spaces having a limited number of varying colors arranged in a pattern with irregularity of occurrence so as to simulate the haphazard appearance of hand-laid tiling, certain of said spaces being replaced by printed tile-like spaces of strikingly

different decorative appearance, said tile-like spaces being separated by printed elongated spaces colored to simulate mortar joints and having said elongated spaces depressed to simulate the depressed joints of hand-laid tiling.

7. A flexible hard-surfaced floor covering having printed thereon a color pattern simulating tiling and brought into relief 10 by having the joints between the tiles depressed below the tiles.

8. A flexible hard-surfaced floor covering having printed thereon a pattern simulating tile separated by mortar joints and brought 15 into relief by having the mortar joints depressed below the tile.

9. A flexible hard-surfaced floor covering

having its entire surface printed with a pattern and brought into relief by having certain colored portions thereof depressed 20 leaving other colored portions standing in undepressed contrast thereto.

10. A flexible hard-surfaced floor covering having printed thereon a colored pattern of varying printed colors, certain of the colors 25 being depressed in shallow recesses of smooth contour, the marginal lines of the recesses substantially coinciding with the lines of juncture between the colors.

In testimony whereof we have hereunto 30 set our hands.

CHARLES F. HUMPHREYS.
JOHN C. McCARTHY.
